QUICK RELEASE ELECTRICAL CONNECTOR
William A. Ellis, 816 N. O St., Space 10, Lompoc, Calif.
Filed Apr. 17, 1961, Ser. No. 103,644
20 Claims. (Cl. 339—12)

This invention relates to electrical connectors generally, and in particular to electrical connectors of the quick release type which may be externally actuated to effect quick disconnection of the cooperating elements of the connector.

While the electrical connector of the present invention is of general application, it finds particular utility in effecting temporary electrical connections between a movable element or vehicle such as a rocket or missile or other air or ground vehicle and a ground station where it is desired to effect quick and reliable disconnection of the electrical circuits interconnecting the vehicle and the ground station. The electrical connector according to the present invention will handle a large number of interconnecting circuits and will enable these circuits to be maintained connected until substantially the time of vehicle movement when the connector may be quickly separated and the circuits simultaneously disconnected. According to an exemplary embodiment of this invention the ground station connected portion of the connector is quickly ejected from the vehicle connected portion and, if not destroyed by the vehicle exhaust, is reusable with another cooperating vehicle portion without rewiring of the ground station portion of the connector.

It is an object of the present invention to provide an improved form of quick release electrical connector providing for reliable disconnection of the connector components upon external actuation.

Another object of this invention is the provision of an electrical connector for a multiplicity of circuits, having means for positively adjusting the relative position of the connector components to adjust the pressure between the cooperating contacts upon such components, and with improved means for effecting release of the connection between said components and for ejecting one of the components from the connector to simultaneously disconnect the circuits through the connector.

A further object of this invention is an electrical connector for a multiplicity of circuits biased for relative separating movement to simultaneously disconnect all of said circuits, with improved means for effecting release of the connection between the cooperating components of the connector to provide for quick relative movement therebetween under said bias.

A still further object of this invention is to provide an improved form of electrical connector for a multiplicity of circuits having means for positively engaging the cooperating components of the connector and forcing the components into contact engaging position with means for effecting the automatic separation of the components to simultaneously disconnect all of the circuits.

Yet another object of this invention is the provision of an improved electrical connector for a multiplicity of circuits providing for a wiping contact surface action and for deformation of resilient contacts to apply a substantial pressure to the contact surfaces.

A still further object of this invention is the provision of an improved quick release electrical connector having a maximum of circuits therethrough and in which connector separation is quick, positive, sure and reliable.

An ancillary object of this invention is to provide an improved contact mounting for an electrical connector.

These and other objects and features of the present invention will be apparent to those skilled in the art from the following specification and the appended drawing, in which:

2

FIGURE 1 is a longitudinal sectional view through the electrical connector of the present invention;

FIGURE 1a is an enlarged detail view of the connecting and releasing means for the cooperating members of the electrical connector of this invention;

FIGURE 2 is an enlarged detail sectional view on the line 2—2 of FIGURE 1;

FIGURE 3 is an end elevational view of the male member of the connector of this invention;

FIGURE 4 is an enlarged detail sectional view of cooperating contacts on the male and female members of the connector of this invention just prior to the instant of contact;

FIGURE 5 is a view similar to FIGURE 4 but showing the contact arrangement with the male and female members fully engaged; and

FIGURE 6 is a detail sectional view showing an alternative contact mounting arrangement.

As specifically illustrated in the drawing, the electrical connector of this invention comprises a relatively stationary female member indicated generally at 11 and composed of molded insulating material, such as Bakelite, and having cooperating therewith a complementary male member 12 also formed of molded insulating material. The female member 11 is provided with a pair of internal surfaces 13 and 14 in the form of truncated cones radially and axially spaced from each other. The male member is provided with complementary truncated cone surfaces externally thereof, as at 15 and 16.

The inner surface 13 of the female member 11 is provided with a plurality of circumferentially spaced notches 17 in which are disposed contact members 18. The contacts 18 includes shank portions 19 within which are secured internal circuit wiring 21. The surface 14 of the female member 11 is similarly provided with a plurality of circumferentially spaced grooves or notches 22 in which are disposed contact members 23 having shank portions 24 connected to internal wiring 25. The notches 17 and 22 and contacts 18 and 23 of the female member are arranged to be complementary to the contacts in the male member shown in the end view of FIGURE 3 and to be described hereinafter.

While only two stages of contacts are shown at the truncated surfaces 13 and 14, it is understood that any desired number of stages and concentric sets of circumferential contacts may be utilized within the limitations of the size of the connector. The angle which the contacts 18 and 23 make with respect to the axis of the connector is preferably not substantially less than 12 degrees, so as to prevent any tendency of the cooperating contacts on the male and female members to seize and prevent the automatic ejection of the male member from the connector.

Within the female member 11 is molded a metallic plate 31 having circumferential holes 32 therethrough, through which extend the shanks 19 of the contacts 18. The plate 31 is provided with a forwardly directed indexing pin 33 which cooperates with a hole 34 in the male member 12 to insure proper indexing of the contacts on the male and female members of the connector. Centrally of the plate 31 there is provided a generally rectangular opening 35 having upper and lower curved beveled surfaces 36 and 37, as shown more particularly in FIGURE 2.

While either member of the connector may be stationary while the other is ejected therefrom, in the specific form illustrated in the drawing the female member 11 has been selected to be the relatively stationary one which is mounted on the movable vehicle, while the movable member 12 is automatically ejected from the female member to interrupt the connections between the internal and external circuits upon operation of the connector.

The truncated conical surface 15 of the male member 12 is provided with a plurality of circumferentially spaced notches 41 to be disposed opposite the notches 17 in the female member 11, and within the notches 41 are disposed contacts 42 cooperating with the contacts 18. The contacts 42 have shanks 43 connected to exterior circuit wiring 44. Similarly, the conical surface 16 on the male member 12 is provided with circumferentially spaced notches 45 to be disposed opposite the notches 22 on the female member 11, and in which are disposed contacts 46 cooperating with the contacts 23. The contacts 46 have shanks 47 connected to exterior circuit wiring 48.

The contacts are so dimensioned that in their bowed shape as shown in FIGURE 4 they engage the ends of the notches in which they are disposed. This prevents a simple sliding action of the contact end and instead restrains the end and requires a further curvature adjacent the ends of the contacts when their engaging surfaces are flattened as in FIGURE 5 engagement.

A metallic plate 49 and a U-shaped bracket 51 are mounted on the front of the male member 12 by means of studs 52. Slidably mounted in openings 53 and 54 in the plate 49 and in the bight of the bracket 51, respectively, is an actuating bolt 55. The outer exterior surface of the bolt 55 is threaded at 56 to receive an elongated nut 57 having a handle 58 and bearing against the outer surface of the bight of the bracket 51. The bolt 55 has a central bore to receive an elongated main operating pin 61 which has a reduced and pointed end portion 62 at its interior end, and a lanyard ring 63 at its outer end.

Adjacent to its interior end the bolt 55 is provided with opposite upper and lower slots 65 and 66 in which are disposed domed rollers 67 and 68, respectively. The rollers 67 and 68 are mounted on axles 69 and 71, respectively, disposed in slots 72 and 73 so that the rollers 67 and 68 may move radially with respect to the bolt 55. The end of the bolt 55 adjacent to the slots 65 and 66 is rectangular in form at 74, as shown in FIGURE 2, and conforms to the rectangular opening 35 in the plate 31 of the female member 11. The reduced end 62 of the pin 61 is disposed between the rollers 67 and 68, as shown in FIGURES 1a and 2, to force the rollers 67 and 68 to their outermost position, as shown in these figures, the rollers 67 and 68 then engaging with the beveled surfaces 36 and 37 on the plate 31. In the innermost position of the pin 61, the bolt 55 and pin 61 have mating openings through which extends a cotter shear pin 75 normally holding the bolt and pin together in this relationship.

Extending through the pin 61 and rigid therewith is a transverse trip pin 76 slidable within a pair of opposite slots 77 in the bolt 55. About the bolt 55 and within the U-shaped bracket 51 is disposed an electromagnetic coil 78, and cooperating therewith is a magnetic armature 79 also surrounding the bolt 55 and having an end surface 81 adapted to engage the trip pin 76 in the attracted position of the armature. A light biasing spring 82 biases the armature 79 into its unattracted position so that it will engage the trip pin 76 with a sharp blow when the electromagnetic coil 78 is energized.

The male member 12 has a bore 83 therethrough through which the bolt 55 slidably extends, and the bore 83 is countersunk at 84 to receive a strong biasing spring 85 whose inner end presses against the plate 31 and applies a biasing force to the male member 12, tending to effect separation of the male member from the female member by ejecting it from the connector. An end 86 on the spring 85 is received within a complementary hole in the male member 12 to retain the spring 85 within the countersink 84. A sealing gasket 87 is disposed in a circular groove in the outer surface of the female member 11 and cooperates with the plate 49 on the male member in sealing relation. The plate 49 is flanged at 88 to interlock with a flexible sealing cover 89 whose outer end is provided with a throat 91 engaging the nut 57 in sealing relation. The external circuit wiring 44 and 48 connected to

the contacts 42 and 46 of the male member of the connector is led through the cover 89 in a cable 92.

The operation of the connector according to the present invention is as follows. With the pin 61 in retracted position, the end 62 thereof frees the rollers 67 and 68 for movement radially inwardly of the bolt 55. The inner end 74 of the bolt 55 is first inserted through the opening 35 in the plate 31, with the male member 12 thus partially inserted into the female member 11. The pin 61 is next fully inserted into the bolt 55 with the end 62 pressing the rollers 67 and 68 radially outwardly into the positions shown in the drawing, in back of the plate 31 and engaged with the bevels 36 and 37 thereon. The shear pin 75 is now inserted in the mating openings in the bolt 55 and pin 61 to maintain the pin in its inserted position relative to the bolt. This locks the male and female members of the connector together. It will be understood that in the previously described operation the nut 57 will have been loosened to permit this operation to be conducted freely. At this time the cooperating contacts of the male and female members are substantially in the position shown in FIGURE 4, just prior to engagement. The nut 51 is now tightened, and by its engagement with the outer surface of the bight of the U-shaped bracket 51, the male member 12 is forced inwardly relative to the female member 11 into full engagement therewith, the bolt 55 being prevented from withdrawing from the plate 31 by the engagement of the rollers 67 and 68 with the bevels 36 and 37. As the male member moves inwardly, the cooperating contacts, as at 46 and 23 in FIGURE 4, engage and move relative to each other with a wiping action. Also, since the contacts are at an angle such that there is a component of movement of the one toward the other, there is a mutual deformation of the contact forms from the normal outwardly bowed positions of FIGURE 4 into the substantially flat positions of FIGURE 5. In this contact movement the ends of the contacts are restrained and must take a sharper bend in order to accommodate the straightening of the contacting surfaces. It will be understood that the contacts are of good conducting but resilient material, such as bronze, and that their deformation from their normal form of FIGURE 4 into the flattened engaged form of FIGURE 5 effects a high contact pressure between the contacting surfaces to provide a good low-resistance contact in the connector.

After the metering, supply, and other functions of the connector circuits have been completed and it is desired to eject the male member from the female member of the connector so that the female member will be free to move off with the vehicle to which it is attached, the electromagnetic coil 78 is energized to attract the armature 79 for movement against the bias of the spring 82. The end surface 81 of the armature 79 then engages the trip pin 76 with a sharp blow, shears the shear pin 75, and moves the operating pin 61 outwardly. This moves the end 62 of the pin 61 into the dotted-line position of FIGURE 1a, so that the rollers 67 and 68 are free to move inwardly. Due to the beveled surfaces 36 and 37, the axial force of the spring 85 exerts a radial component of force on the rollers 67 and 68 so that they move inwardly and free the bolt 55 for movement outwardly relative to the plate 31. Since the bolt 55 provided the only connection between the male and female members, the spring 85 now moves the male member 12 axially outwardly and ejects it from the female member, and simultaneously separates all of the cooperating contacts 18-42 and 23-46. This frees the female member 11 from all connection to the ground station, so that it may move with the vehicle on which it is mounted without exterior resistance.

It will be apparent that the operating pin 61 may also be manually released by pulling on the lanyard connected to the ring 63, which will shear the pin 75 and move the pin 61 outwardly to release the connection between male

and female members of the connector as previously described.

In the event the male member is not injured or destroyed by the blast from the vehicle to which the connector is attached, it is apparent that it may be reused in the manner described with a new or the same female member 11.

FIGURE 6 shows an alternative mounting for a stationary contact 23 mounted in a notch 22 in the female member 11, in which there is disposed between the contact 23 and the back of the notch 22 a cold flow plastic material 93 which, when the contacts are engaged, must flow toward the opposite ends of the contact, thus serving to back up the contact to increase the contact pressure between the cooperating contacts.

From the foregoing description it will be seen that applicant's connector may be readily assembled and then, by manipulation of the nut 57, the male and female members be brought tightly together to secure a wiping action on the inclined cooperating contacts on the male and female members, and a deformation of their normal shapes to secure a relatively high contact pressure therebetween. It will further be seen that the connector is released by a relatively light force required to shear the light pin 75 and to move the pin 61 axially. Thereafter the radial components of force exerted by the bevels 36 and 37 will move the rollers 67 and 68 inwardly so that the bolt 55 is freed from the plate 31, and the male member 12 is then separated or ejected from the female member under the bias of the spring 85. The release is quick, positive, sure, and reliable, and results in separation or ejection of the male member, with simultaneous separation of the cooperating contacts of the connector. At the same time, the connector when in assembled position affords a low-resistance, high-pressure wiping contact engagement between the cooperating contacts on the male and female members thereof.

While a certain preferred embodiment of the invention has been specifically shown and described, it will be understood that the invention is not limited thereto as many variations will be apparent to those skilled in the art, and the invention is to be given its broadest interpretation within the terms of the following claims.

I claim:

1. An electrical connector comprising: a pair of engageable and separable members; a plurality of contacts on each said members, said contacts being mounted substantially in a ring in circumferentially spaced relation; means for indexing said members so that the contacts on one of said members cooperate with the contacts on the other of said members to establish a plurality of electrical circuits through the connector, said contacts being mounted with their engaging surfaces at an acute angle to the direction of relative movement of said members and engaging prior to complete engagement of said members to provide for relative wiping movement of said contacts, said contacts being substantially longitudinally bowed and being restrained against longitudinal movement of both ends of the bows, said bows flattening with increased curvature adjacent the ends thereof as the contacts fully engage to provide contact pressure between the cooperating contacts; means for positively moving said members into engaged position with said contacts deformed; and means for effecting relative disengaging movement of said members at will.

2. An electrical connector comprising: a pair of engageable and separable members; a plurality of contacts on each said members, said contacts being mounted substantially in a ring in circumferentially spaced relation; means for indexing said members so that the contacts on one of said members cooperate with the contacts on the other of said members to establish a plurality of electrical circuits through the connector, said contacts being mounted with their engaging surfaces at an acute angle to the direction of relative movement of said members and en-

gaging prior to complete engagement of said members to provide for relative wiping movement of said contacts, said contacts being substantially longitudinally bowed and being restrained against longitudinal movement of both ends of the bows, said bows flattening with increased curvature adjacent the ends thereof as the contacts fully engage to provide contact pressure between the cooperating contacts; a cold flow plastic material backing said contacts to be deformed therewith; means for positively moving said members into engaged position with said contacts deformed; and means for effecting relative disengaging movement of said members at will.

3. An electrical connector comprising: a pair of engageable and separable members; a plurality of contacts on each said members, said contacts being mounted substantially in a ring in circumferentially spaced relation; means for indexing said members so that the contacts on one of said members cooperate with the contacts on the other of said members to establish a plurality of electrical circuits through the connector, said contacts being mounted with their engaging surfaces at an acute angle to the direction of relative movement of said members and engaging prior to complete engagement of said members to provide for relative wiping movement of said contacts, said contacts being formed of resilient material and being arranged to be deformed without deformation of said members to provide contact pressure between the cooperating contacts; means for positively moving said members into engaged position with said contacts deformed; means independent of said contacts biasing said members for relative separating movement; means for locking said members in engaged position; and means for releasing said locking means to effect relative movement between said members under the action of said biasing means to separate the connector.

4. An electrical connector comprising: a pair of engageable and separate members; a plurality of contacts on each said members, said contacts being mounted substantially in a ring in circumferentially spaced relation; means for indexing said members so that the contacts on one of said members cooperate with the contacts on the other of said members to establish a plurality of electrical circuits through the connector, said contacts being mounted with their engaging surfaces at an acute angle to the direction of relative movement of said members and engaging prior to complete engagement of said members to provide for relative wiping movement of said contacts, said contacts having a longitudinally bowed shape and being restrained against longitudinal movement of both ends of the bows, said bows flattening as the contacts fully engage to provide contact pressure between the cooperating contacts; means for positively moving said members into engaged position with said contacts deformed, said last mentioned means including means interconnecting said members having adjusting means for positively drawing said members together into engaged position to stress said contacts; means independent of said contacts biasing said members for relative separating movement therebetween; and means for releasing said interconnecting means at will to provide for quick automatic separation of said members and cooperating contacts under the action of said biasing means.

5. An electrical connector comprising: a pair of engageable and separable members; a multiplicity of electrical contacts on each of said members arranged substantially in ring formation and circumferentially spaced apart; means for indexing said members so that in engaged position the contacts thereon will cooperate to establish a multiplicity of circuits through the connector; connecting means mounted on one of said members and releasably engageable with the other of said members; means for positively moving said connecting means to force said members into engagement to effect deformation of the cooperating contacts under stress to establish a substantial contact pressure therebetween and effect a low resistance connection, said connecting means including elements

movable into extended and retracted position and normally held in extended position to effect the connection between said members; means independent of said contacts biasing said members for relative separating movement; and means for releasing said elements for movement into retracted position to release the connection between said members for quick and positive simultaneous disconnection of said contacts by relative separating movement of said members.

6. An electrical connector comprising: a pair of engageable and separable members; a multiplicity of electrical contacts on each of said members arranged substantially in ring formation and circumferentially spaced apart; means for indexing said members so that in engaged position the contacts thereon will cooperate to establish a multiplicity of circuits through the connector; connecting means mounted on one of said members and releasably engageable with the other of said members; means for positively moving said connecting means to force said members into engagement to effect deformation of the cooperating contacts under stress to establish a substantial contact pressure therebetween and effect a low resistance connection, said connecting means including elements movable into extended and retracted position and normally held in extended position to effect the connection between said members; means independent of said contacts biasing said members for relative separating movement; and electromagnetic means operable when energized to release said elements for movement into retracted position to break the connection between said members and effect quick separation of said members under the action of said biasing means with simultaneous interruption of the multiplicity of circuits through said connector.

7. An electrical connector comprising: a pair of engageable and separable members; a multiplicity of electrical contacts on each of said members arranged substantially in ring formation and circumferentially spaced apart; means for indexing said members so that in engaged position the contacts thereon will cooperate to establish a multiplicity of circuits through the connector; connecting means mounted on one of said members and releasably engageable with the other of said members; means for positively moving said connecting means to force said members into engagement to effect deformation of the cooperating contacts under stress to establish a substantial contact pressure therebetween and effect a low resistance connection, said connecting means including elements movable into extended and retracted position and normally held in extended position to effect the connection between said members; means independent of said contacts biasing said members for relative separating movement; and means for releasing said elements for movement into retracted position to release the connection between said members for quick and positive simultaneous disconnection of said contacts by relative separating movement of said members, said contacts being arranged with their engaging surfaces at an acute angle to the direction of relative movement between said members to provide for a wiping action between said contacts, said contacts having a normally substantially longitudinally bowed shape which is flattened upon full engagement of said contacts and being restrained against longitudinal movement of both ends of the bows during such flattening, and said contacts being formed of resilient material tending to reestablish their original bowed shapes so as to effect a substantial contact pressure between the contacts.

8. An electrical connector comprising: cooperating male and female members of insulating material, said female member having a plurality of separate, concentric, discontinuous, axially and radially spaced truncated conical surfaces, and said male member having a plurality of complementary separate, concentric, discontinuous, radially and axially spaced truncated conical surfaces; a multiplicity of contacts mounted on each of said conical sur-

10

faces circumferentially spaced in a ring, said contacts being located so that upon engagement of said male member in said female member the contacts thereon will cooperate to establish a multiplicity of circuits through the connector, said contacts being formed of resilient material and being arranged to be deformed without deformation of said members upon engagement of said male member in said female member; means interconnecting said male and female members and including means for positively forcing said male member into the female member to effect said contact deformation and establish a substantial contact pressure between the cooperating contacts; means for releasing said interconnecting means between said members; and means for withdrawing said male member from said female member to effect separation of the connector.

15

9. An electrical connector comprising: cooperating male and female members of insulating material, said female member having a plurality of separate, concentric, discontinuous, axially and radially spaced truncated conical surfaces, and said male member having a plurality of complementary separate, concentric, discontinuous, radially and axially spaced truncated conical surfaces; a multiplicity of contacts mounted on each of said conical sur-

20

faces circumferentially spaced in a ring, said contacts being located so that upon engagement of said male member in said female member the contacts thereon will cooperate to establish a multiplicity of circuits through the connector, said contacts being arranged so that their contact surfaces extend at an acute angle to the direction of

25

movement of said male member to provide for a wiping action between said contacts as the male member fully enters the female member, said contacts being formed of resilient material and being arranged to be deformed

30

without deformation of said members upon engagement of said male member in said female member; means interconnecting said male and female members and including means for positively forcing said male member into the female member to effect said contact deformation and establish a substantial contact pressure between the cooperating contacts; means for releasing said interconnecting means between said members; and means for withdrawing said male member from said female member to effect separation of the connector.

35

10. An electrical connector comprising: cooperating male and female members of insulating material, said female member having a plurality of separate, concentric, discontinuous, axially and radially spaced truncated conical surfaces, and said male member having a plurality of complementary separate, concentric, discontinuous, radially and axially spaced truncated conical surfaces; a multiplicity of contacts mounted on each of said conical sur-

40

faces circumferentially spaced in a ring, said contacts being located so that upon engagement of said male member in said female member the contacts thereon will cooperate to establish a multiplicity of circuits through the connector, said contacts being arranged so that their contact surfaces extend at an acute angle to the direction of

45

movement of said male member to provide for a wiping action between said contacts as the male member fully enters the female member, said contacts being formed of resilient material and being arranged to be deformed

50

without deformation of said members upon engagement of said male member in said female member; means interconnecting said male and female members and including means for positively forcing said male member into the female member to effect said contact deformation and establish a substantial contact pressure between the cooperating contacts; means for releasing said interconnecting means between said members; and means for withdrawing said male member from said female member to effect separation of the connector.

55

11. An electrical connector comprising: cooperating male and female members of insulating material, said female member having a plurality of separate, concentric, discontinuous, axially and radially spaced truncated conical surfaces, and said male member having a plurality of complementary separate, concentric, discontinuous, radially and axially spaced truncated conical surfaces; a multiplicity of contacts mounted on each of said conical sur-

60

faces circumferentially spaced in a ring, said contacts being located so that upon engagement of said male member in said female member the contacts thereon will cooperate to establish a multiplicity of circuits through the connector, said contacts being formed of resilient material and being arranged to be deformed without deformation of said members upon engagement of said male member in said female member; means interconnecting said male and female members and including means for positively forcing said male member into the female member to effect said contact deformation and establish a substantial contact pressure between the cooperating contacts; means for releasing the interconnecting means between said members to provide for quick ejection of the male member from the female member to effect separation of said connector and freeing of said member.

65

12. An electrical connector comprising: cooperating male and female members of insulating material, said female member having a plurality of separate, concentric, discontinuous, axially and radially spaced truncated conical surfaces, and said male member having a plurality of

70

complementary separate, concentric, discontinuous, radially and axially spaced truncated conical surfaces; a multiplicity of contacts mounted on each of said conical sur-

75

faces circumferentially spaced in a ring, said contacts being located so that upon engagement of said male member in said female member the contacts thereon will cooperate to establish a multiplicity of circuits through the connector, said contacts being formed of resilient material and being arranged to be deformed without deformation of said members upon engagement of said male member in said female member; means interconnecting said male and female members and including means for positively forcing said male member into the female member to effect said contact deformation and establish a substantial contact pressure between the cooperating contacts; means for releasing the interconnecting means between said members to provide for quick ejection of the male member from the female member to effect separation of said connector and freeing of said member.

80

13. An electrical connector comprising: cooperating male and female members of insulating material, said female member having a plurality of separate, concentric, discontinuous, axially and radially spaced truncated conical surfaces, and said male member having a plurality of

85

complementary separate, concentric, discontinuous, radially and axially spaced truncated conical surfaces; a multiplicity of contacts mounted on each of said conical sur-

90

faces circumferentially spaced in a ring, said contacts being located so that upon engagement of said male member in said female member the contacts thereon will cooperate to establish a multiplicity of circuits through the connector, said contacts being formed of resilient material and being arranged to be deformed without deformation of said members upon engagement of said male member in said female member; means interconnecting said male and female members and including means for positively forcing said male member into the female member to effect said contact deformation and establish a substantial contact pressure between the cooperating contacts; means for releasing the interconnecting means between said members to provide for quick ejection of the male member from the female member to effect separation of said connector and freeing of said member.

95

14. An electrical connector comprising: cooperating male and female members of insulating material, said female member having a plurality of separate, concentric, discontinuous, axially and radially spaced truncated conical surfaces, and said male member having a plurality of

100

complementary separate, concentric, discontinuous, radially and axially spaced truncated conical surfaces; a multiplicity of contacts mounted on each of said conical sur-

105

faces circumferentially spaced in a ring, said contacts being located so that upon engagement of said male member in said female member the contacts thereon will cooperate to establish a multiplicity of circuits through the connector, said contacts being formed of resilient material and being arranged to be deformed without deformation of said members upon engagement of said male member in said female member; means interconnecting said male and female members and including means for positively forcing said male member into the female member to effect said contact deformation and establish a substantial contact pressure between the cooperating contacts; means for releasing the interconnecting means between said members to provide for quick ejection of the male member from the female member to effect separation of said connector and freeing of said member.

complementary separate, concentric, discontinuous, radially and axially spaced truncated conical surfaces; a multiplicity of contacts mounted on each of said conical surfaces circumferentially spaced in a ring, said contacts being located so that upon engagement of said male member in said female member the contacts thereon will cooperate to establish a multiplicity of circuits through the connector, said contacts being formed of resilient material and being arranged to be deformed without deformation of said members upon engagement of said male member in said female member; means interconnecting said male and female members and including means for positively forcing said male member into the female member to effect said contact deformation and establish a substantial contact pressure between the cooperating contacts; means independent of said contacts biasing said male member for ejection from said female member; and electromagnetic means for releasing the interconnecting means between said members to effect ejection of said male member and simultaneous quick disconnection of the multiplicity of circuits through said connector.

12. An electrical connector comprising: a pair of engageable and separable insulating members; a plurality of contacts on each of said members, said contacts being circumferentially spaced in concentric rings on each of said members and located so as to cooperate when said members are engaged to establish a multiplicity of circuits through the connector, said contacts being longitudinally bowed and formed of resilient material; means limiting the length of said contacts; means for positively forcing said members into engagement so as to flatten said contacts with increased curvature adjacent the ends of the bows to establish a substantial contact pressure therebetween; means for releasing said members; and means for effecting relative separating movement between said members to disconnect said connector.

13. An electrical connector comprising: a pair of engageable and separable insulating members; a plurality of contacts on each of said members, said contacts being circumferentially spaced in concentric rings on each of said members and located so as to cooperate when said members are engaged to establish a multiplicity of circuits through the connector, said contacts being formed of resilient material and being deformable without deformation of said members; means for positively forcing said members into engagement so as to deform said contacts without deforming said members to establish a substantial contact pressure therebetween; means for releasing said members; and means for effecting relative separating movement between said members to disconnect said connector, said last mentioned means comprising biasing means independent of said contacts operating when said members are released to effect quick relative movement between said members to effect quick disconnection of said connector and simultaneous interruption of said multiplicity of circuits.

14. An electrical connector comprising: a pair of engageable and separable insulating members; a plurality of contacts on each of said members, said contacts being circumferentially spaced in concentric rings on each of said members and located so as to cooperate when said members are engaged to establish a multiplicity of circuits through the connector, said contacts being longitudinally bowed and formed of resilient material; means limiting the length of said contacts; means for positively forcing said members into engagement, said contacts being arranged with their contacting surfaces at an acute angle to the direction of relative movement of said members, and said contact surfaces engaging prior to the complete engagement of said members so as to effect both a wiping and flattening action of the contact surfaces with increase in curvature adjacent the ends of the bows; means for releasing said members; and means for effecting relative separating movement between said members to disconnect said connector.

5 15. An electrical connector comprising: a pair of engageable and separable insulating members; a plurality of contacts on each of said members, said contacts being circumferentially spaced in concentric rings on each of said members and located so as to cooperate when said members are engaged to establish a multiplicity of circuits through the connector, said contacts being formed of resilient material and being deformable without deformation of said members; means for positively forcing said members into engagement, said contacts being arranged with their contacting surfaces at an acute angle to the direction of relative movement of said members, and said contact surfaces engaging prior to the complete engagement of said members so as to effect both a wiping and deforming action of the contact surfaces without deforming said members; means for positively locking said members in engaged position; electromagnetic and manual means for releasing said positive locking means; and means independent of said contacts for biasing said members for quick relative disconnecting movement when released.

10 16. An electrical connector comprising: cooperating male and female members of insulating material; a plurality of electrical contacts on each of said members, said contacts being arranged in circumferentially spaced relation in axially and radially spaced concentric rings on each 15 of said members; means for indexing said members so that in engaged position the contacts thereon cooperate to establish a multiplicity of circuits through the connector, said contacts being arranged so that their engaging surfaces are disposed at an acute angle to the direction of movement of said male member and positioned to be engaged prior to complete insertion of said male member in the female member so that a wiping action occurs at the cooperating contact surfaces, said contacts being formed 20 of resilient material and being deformed as said male member completely enters said female member without deformation of either member so as to establish a substantial contact pressure between the cooperating contact surfaces; means for positively inserting said male member into said female member to effect said wiping and deforming action of said contact surfaces without deforming either of said members; and means for releasing said last 25 mentioned means to provide for removal of said male member from said female member to disconnect said connector.

30 17. An electrical connector comprising: cooperating male and female members of insulating material; a plurality of electrical contacts on each of said members, said contacts being arranged in circumferentially spaced relation in axially and radially spaced concentric rings on each 35 of said members; means for indexing said members so that in engaged position the contacts thereon cooperate to establish a multiplicity of circuits through the connector, said contacts being arranged so that their engaging surfaces are disposed at an acute angle to the direction of movement of said male member and positioned to be engaged prior to complete insertion of said male member in the female member so that a wiping action occurs at the cooperating contact surfaces, said contacts being formed 40 of resilient material and being deformed as said male member completely enters said female member without deformation of either member so as to establish a substantial contact pressure between the cooperating contact surfaces; means interconnecting said male and female members and including adjusting means for positively forcing said male member into said female member to effect the wiping and deforming action of the contact surfaces without deforming either of said members; means independent of said contacts biasing said male member for ejection from said female member; and means for 45 releasing said interconnecting means at will to provide for quick ejection of said male member and separation of the connector.

45 18. An electrical connector comprising: cooperating male and female members of insulating material; a plu- 50

rality of electrical contacts on each of said members, said contacts being arranged in circumferentially spaced relation in axially and radially spaced concentric rings on each of said members; means for indexing said members so that in engaged position the contacts thereon cooperate to establish a multiplicity of circuits through the connector, said contacts being arranged so that their engaging surfaces are disposed at an acute angle to the direction of movement of said male member and positioned to be engaged prior to complete insertion of said male member in the female member so that a wiping action occurs at the cooperating contact surfaces, said contacts being formed of resilient material and being deformed as said male member completely enters said female member without deformation of either member so as to establish a substantial contact pressure between the cooperating contact surfaces; a bolt slidably extending through the axis of said male member and having means at its inner end interlocking with said female member; a nut threaded on the exterior end of said bolt and operable to force said male member into said female member to effect said contact surface wiping and deforming action without deforming either of said members; means independent of said contacts biasing said male member for ejection from said female member; and electromagnetic means for releasing said interlock between said bolt and said female member to provide for quick ejection movement of said male member and separation of said connector.

19. An electrical connector comprising: cooperating male and female members of insulating material; a plurality of electrical contacts on each of said members, said contacts being arranged in circumferentially spaced relation in axially and radially spaced concentric rings on each of said members; means for indexing said members so that in engaged position the contacts thereon cooperate to establish a multiplicity of circuits through the connector, said contacts being arranged so that their engaging surfaces are disposed at an acute angle to the direction of movement of said male member and positioned to be engaged prior to complete insertion of said male member in the female member so that a wiping action occurs at the cooperating contact surfaces, said contacts being formed of resilient material and being deformed as said male member completely enters said female member so as to establish a substantial contact pressure between the 45 cooperating contact surfaces; a bolt slidably extending through the axis of said male member and having means at its inner end interlocking with said female member; a nut threaded on the exterior end of said bolt and operable to force said male member into said female member to effect said contact wiping and deforming action; means biasing said male member for ejection from said female member; said interlock means including elements extendable and retractable radially of said bolt into engagement with a back surface on said female member, said back 55 surface being inclined to the axis of said bolt so as to exert a radial component of force on said elements; means disposable between said elements to force them into extended and locking relation with respect to said back surface; and electromagnetic means for withdrawing said 60

means disposed between said elements to provide for radial retracting movement thereof and release of said back surface to free said male member for rapid ejection from said female member under said biasing means to effect separation of said connector and simultaneous disconnection of the multiplicity of circuits therethrough.

5 20. An electrical connector comprising: cooperating male and female members of insulating material; a plurality of electrical contacts on each of said members, said contacts being arranged in circumferentially spaced relation in axially and radially spaced concentric rings on each of said members; means for indexing said members so that in engaged position the contacts thereon cooperate to establish a multiplicity of circuits through the connector, said contacts being arranged so that their engaging surfaces are disposed at an acute angle to the direction of movement of said male member and positioned to be engaged prior to complete insertion of said male member in the female member so that a wiping action occurs at the cooperating contact surfaces, said contacts being formed of resilient material and being deformed as said male member completely enters said female member so as to establish a substantial contact pressure between the cooperating contact surfaces; a bolt slidably extending through the axis of said male member and having means at its inner end interlocking with said female member; a nut threaded on the exterior end of said bolt and operable to force said male member into said female member to effect said contact surface wiping and deforming action; means biasing said male member for ejection from said female member; said interlock means including elements extendable and retractable radially of said bolt into engagement with a back surface on said female member, said back surface being inclined to the axis of said bolt so as to exert a radial component of force on said elements; means disposable between said elements to provide for radial retracting movement thereof and release of said back surface to free said male member for rapid ejection from said female member under said biasing means to effect separation of said connector and simultaneous disconnection of the multiplicity of circuits therethrough; said 35 extendable and retractable elements comprising rollers rotatably and slidably mounted in the interior end of said bolt, and said release means comprising both electromagnetic and manually operable means for withdrawing the means disposed between said rollers.
